ELECTRICAL CONNECTOR

Edward A. Sprigg, Toledo, Ohio, assignor to H. H. Buggie & Company, Toledo, Ohio, a corporation of Ohio

Application December 18, 1944, Serial No. 568,720

7 Claims. (Cl. 174—77)

1

The invention relates to electrical connectors for connecting an electrically operable element to a source of electrical energy.

The invention has for one of its objects to provide an improved electrical connector which is constructed to have an effective water and air seal.

The invention has for other objects to construct the electrical connector with the sealing member bonded to the electrical contacts of the electrical connector and also to construct the electrical conductor with the sealing member displaced into tight engagement with the shell of the electrical connector.

The invention has for a further object to provide an improved means for mounting the electrical connector.

With these as well as other objects in view, the invention resides in the novel features of construction and combinations and arrangements of parts as more fully hereinafter set forth.

In the drawings:

Figure 1 is an end view of the electrical connector embodying the invention;

Figure 2 is a cross section on the line 2—2 of Figure 1.

The electrical connector comprises the metal shell 1, the insulator body 2, the sealing device 3, the pressure device 4, and the electrical contacts 5, the insulator body, sealing device and pressure device being located within the shell.

The shell has the externally threaded end portions 6 and 7, the internal annular flange 8 and the external annular flange 9. The internal annular flange provides the shoulders 10 and 11 which are spaced from each other longitudinally of the shell. The insulator body is in the nature of a plate and is formed with the holes 12 extending longitudinally therethrough for receiving the electrical contacts 5. The insulator body also has the annular flange 13 for overlying and engaging the annular shoulder 10 of the shell and the beveled surface 14 extending from the edge of the annular flange. The annular flange 13 is preferably provided with an opening to receive the positioning pin 15 located in the internal annular flange 8.

The sealing device comprises the yieldable sealing member 16 and the insulator pressure plate 17, the sealing member being preferably formed of synthetic rubber. The sealing member has a plate-like body portion at one side of the pressure plate 17 and engageable with the insulator body 2 and also has an annular flange portion encircling the pressure plate 17 and terminating in the

2

enlargement 18 located within the annular recess 19 at the periphery of the pressure plate. The pressure plate is formed with transverse holes in axial alignment with the holes 12 of the insulator body 2 to receive the electrical contacts 5. The sealing member 16 tightly encircles and is bonded to the electrical contacts around their peripheries. The sealing member is bonded to the pressure plate to form the sealing unit, the bonding in both instances being effected as by vulcanizing the sealing member to the electrical contacts and pressure plate in a mold.

The pressure device 4 comprises the metal pressure ring 20 and the metal follower ring 21 abutting the pressure ring and externally threaded to engage the internal threads 22 of the end portion 7 of the shell. The pressure ring preferably has a rounded face engaging the enlargement 18. The end portion 7 at the inner end of the internal threads 22 is provided with the internal annular recess 23 between the shell and the lower unbeveled edge of backing plate 17.

As shown in the present instance, the electrical contacts 5 are contact pins and they have the enlarged portions 24 and 25 located at the ends of the portions of the sealing member 16 which are bonded to the contact pins.

The end portion 6 of the shell is preferably provided with one or more pins 26 forming in effect a key for engagement with a keyway in the electrical element to be inserted into the end portion whereby the contacts of the electrical element will properly engage the contact pins.

The external annular flange 9 of the shell is used in clamping the electrical connector to the mounting plate 27 and this flange is formed with the annular serrations or teeth 28 which are imbedded in the yieldable sealing member 29 preferably formed of synthetic rubber. I have also preferably provided the pin 30 which extends transversely from the annular flange 9 through the sealing member and into a hole in the mounting plate, this pin serving to properly position the electrical connector on the mounting plate. 31 is a clamping nut threaded upon the end portion 6 of the shell and abutting the mounting plate 27 and serving to effectively clamp the electrical connector to the mounting plate, at which time the yieldable sealing member forms an effective seal.

The construction of the electrical connector is such that after the insulator body 2, the sealing device 3 and the pressure device 4 have been inserted into the shell 1 and the follower ring 21 of the pressure device is tightened down, it exerts

through the pressure ring 20 of the pressure device pressure directly upon the enlargement 18 of the yieldable sealing member 16 and indirectly upon the pressure plate 17. As a result, the body portion of the sealing member 16 is urged firmly against the insulator body 2 and the annular shoulder 11 and the adjacent cylindrical face of the shell. Also the annular enlargement 18 of the sealing member 16 is displaced to compel an additional portion thereof to enter the internal 10 annular recess 23 in the shell and also to compel the adjacent portion of the annular enlargement to tightly engage the adjacent threads 22. It will thus be seen that an effective water and air seal is provided since the sealing device tightly engages the shell and is bonded to the contact pins passing therethrough.

What I claim as my invention is:

1. An electrical connector comprising a shell, a body within said shell having a hole extending therethrough longitudinally of said shell, a sealing device within said shell comprising a pressure plate and a yieldable sealing member bonded to said plate, said sealing member having a body portion at one side of the plate and an annular flange portion encircling said plate and terminating in an annular enlargement, an electrical contact extending within the hole in said body and through said pressure plate and sealing member and bonded around its periphery to said sealing member, and means within said shell exerting pressure upon said enlargement to hold said sealing member against said body and to displace said sealing member into tight engagement with said shell.

2. An electrical connector comprising a shell, a body within said shell having a hole extending therethrough longitudinally of said shell, a sealing device within said shell comprising a pressure plate and a yieldable sealing member bonded to said plate, said sealing member having a body portion at one side of said plate and an annular flange portion encircling said plate and terminating in an annular enlargement, an electrical contact extending within the hole in said body and through said plate and sealing member and bonded to said sealing member, and means within said shell engaging said annular enlargement and exerting pressure upon said plate to displace said enlargement into tight engagement with said shell.

3. An electrical connector comprising a shell having an internal annular groove, a body within said shell having a hole extending therethrough longitudinally of said shell, a sealing device within said shell comprising a pressure plate and a yieldable sealing member bonded to said plate, said sealing member having a body portion at one side of said plate and an annular flange portion encircling said plate and terminating in an annular enlargement, a contact member extending within the hole in said body and through said plate and sealing member and bonded to said sealing member, and means within said shell engaging said annular enlargement and exerting pressure upon said plate to hold said body portion of said sealing member against said body and to displace said body portion into tight engagement with said shell and said annular enlargement into said annular groove.

4. In an electrical connector comprising a shell, a body within said shell, a sealing device within

5 said shell comprising a pressure plate, a yieldable sealing member between said plate and said body, yieldable means surrounding the peripheral portion of the plate and having a portion overlying the side of the plate opposite the side engaged with the sealing member, an electrical contact extending through and bonded to said sealing device, and means within said shell engaging said sealing means to displace the latter into tight engagement with said shell and said plate and to exert pressure upon said plate to hold said sealing member against said body and said shell.

15 6. An electrical connector comprising a shell, a body within said shell, a sealing device within said shell comprising a pressure plate and a yieldable sealing member bonded to said plate, said sealing member having a body portion at one side of said plate and an annular flange portion encircling said plate and terminating in an annular 20 enlargement, an electrical contact extending through and bonded to said sealing device, and means within said shell engaging said annular enlargement to displace the annular enlargement into tight engagement with said shell and said plate and to exert pressure upon said plate to hold said sealing member against said body and said shell.

25 7. An electrical connector comprising a shell, a body within said shell, a sealing device within said shell and engaging said body, said sealing device comprising a pressure plate and a yieldable sealing member having a body portion at one side of the plate and an annular flange portion encircling said plate and terminating in an annular 30 enlargement, an electrical contact extending through and bonded to said sealing member, and means within said shell exerting pressure upon said enlargement to hold said sealing member against said body and to displace said sealing member into tight engagement with said shell.

35 8. An electrical connector comprising a shell, a body within said shell, a sealing device within said shell and engaging said body, said sealing device comprising a pressure plate and a yieldable sealing member having a body portion at one side of the plate and an annular flange portion encircling said plate and terminating in an annular 40 enlargement, an electrical contact extending through and bonded to said sealing member, and means within said shell exerting pressure upon said enlargement to hold said sealing member against said body, said body having a beveled portion engaging said sealing member assisting in displacing said sealing member into tight engagement with said shell.
